Primary Examiner — Omeed Agilee*Assistant Examiner* — David Truong(57) **CLAIM**

The ornamental design for a multifunctional soft buttocks training box, as shown and described.

DESCRIPTION

FIG. 1 is a perspective view of a multifunctional soft buttocks training box showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a partially enlarged view of area 8 shown in FIG. 1.

The broken lines in the drawings depict the boundaries of the enlarged views and form no part of the claimed design.

1 Claim, 8 Drawing Sheets(56)
